UNITED STATES PATENT OFFICE.

MILTON M. BLUM, OF BIRMINGHAM, ALABAMA.

TYPE-WRITER LOCK MECHANISM.

1,174,305.

Specification of Letters Patent. Patented Mar. 7, 1916.

Application filed September 11, 1915. Serial No. 50,267.

To all whom it may concern:

Be it known that I, MILTON M. BLUM, a citizen of the United States of America, residing at Birmingham, in the county of 5 Jefferson and State of Alabama, have invented certain new and useful Improvements in Type-Writer Lock Mechanism, of which the following is a specification.

My invention relates to means for locking 10 the type bar levers and the carriage of a typewriter so that any manipulation or movement of the latter can be positively prevented not only during the shipment of the machine but when the machine is in 15 service and the operator desires to prevent tampering with it in his or her absence.

The chief object of my present invention is to take advantage of certain features of 20 construction which are characteristic of the majority of typewriters in making effectual the locking of both the type bar levers and the carriage, and both of these ends are preferably attained in my invention by 25 means of a single lock which is permanently attached to the typewriter frame.

One feature of my invention relates to 30 the design of the key actuated locking member for the parts to be locked and I propose to design this member so that in its locked position it will embrace the parts 35 it operates so as to itself constitute a means for effectually securing the lock against detachment from the typewriter. In other words, the lock bolt, which as shown is in the form of a bent rod, is adapted to so engage 40 the carriage or the line lock bail, or both the carriage and the line lock bail, that in its locked position it will constitute a part of the attaching means for the lock itself which would hold the lock even if its 45 attaching means to the frame were removed.

In connection with the locking of the type 50 bar levers and the other key controlled functions of the typewriter, I propose to adapt my key actuated lock to engage and lock the universal bar and in accomplishing this, as a preferred means, I have designed my lock means to engage the line lock bail and force the latter into position 55 to lock the universal bar for by this means I obtain a positive lock of the universal bar without subjecting the key controlled mechanism to any appreciable strain.

In connection with the locking of the 60 carriage I have designed a lock element

which is bent to engage under and be braced by the overhanging side flange of the machine top and is movable from rear to front of the machine to engage a part of the carriage, preferably the depending draw strap 60 stud and thus hold the carriage against movement.

My invention further comprises the novel details of construction and arrangement of parts which in their preferred embodiment 65 only are hereinafter more particularly described and illustrated by reference to the accompanying drawings which form a part of this specification, and in which:—

Figure 1 is a side elevation of an L. C. 70 Smith typewriter which I have chosen to illustrate my invention but without intending thereby to limit myself to such type of machine. Fig. 2 is a perspective view of the lock mechanism with the typewriter 75 parts shown with which it operates in performing its locking function. Fig. 3 is a detail internal view of the lock with its front cover removed. Figs. 4 and 5 are detail views of the yoke ends on the locking 80 bar.

Similar reference numerals refer to similar parts throughout the drawings.

I have illustrated a typewriter machine comprising a base 1, front and rear uprights 2, a side plate 3 connected to the uprights, and a top cover plate 4, which latter has an overhung depending side flange 5. The typewriter is provided with the customary arrangement of type bar levers 6 connected by sub-levers 7 to the several type bars 8 which are adapted to strike the platen 9 mounted upon a movable carriage 10, which parts are all of standard 85 construction and form no particular part of my present invention. The typewriter is provided with a universal bar 11 of standard construction mounted upon a bracket 12 and having exposed to the rear of it a line lock bail 13 suitably pivoted to 90 brackets 14 at its rear corner edges and provided along its length with slots 15. This line lock bail is adapted when rocked by its operating bell crank (not shown) to engage 95 and lock the universal bar so as to hold it 100 in position to lock the type and control bar levers of the machine against manipulation. The carriage has rigidly mounted thereon a depending draw strap stud 16 to which the carriage draw strap 17 is attached. It 110

will be noted that the strap leaves a substantial portion of the stud exposed above it so that it is peculiarly adapted to serve as the part to be engaged by my lock to prevent the movement of the carriage. All of the parts so far described are of standard construction and need no modification to be adapted to my present purposes.

My lock mechanism comprises a casing 18 having an integral or a soldered top plate 19 and having an extension flange 20 at one end which laps over the rear face of the side plate and is intended to be riveted or permanently attached thereto with the lock barrel 21 seated in the lower rear corner of the center opening in the side plate which thus braces the lock against displacement and affords a firm attachment for it to the frame. The lock, which is the type described in my pending application, Serial No. 13,931, need not be described in detail in this case beyond stating that it comprises a slide 22 which is provided with an arcuate slot 23 in which a pin 24, disposed eccentric to the key rotated portion of the lock, is received and as the lock is turned the pin will shift the slide from full to dotted line position, as shown in Fig. 3, and vice versa. A lock bar 25 is made fast to the slide and passed through suitable openings in each end of the casing 18. The rear end of this lock bar, designated as 25^a, constitutes the type bar lever locking element. It is bent inwardly crosswise of the machine and upwardly and has its end bent toward the front of the machine where it is provided with a yoke 26 comprising an elongated bottom arm 27. The yoke arms are provided with alining slots 28 in which a headed pin 29 is slidably received. This yoke is adapted to straddle the line lock bail 13 with the pin 29 passing through the slot 15 therein. The lower arm 27 of the yoke passes under the line lock bail and into position to engage and lock the universal bar 11 when the yoke stands in the full line position shown in Fig. 2. At the same time the upper arm of the yoke will engage and force downwardly the line lock bail so as to move the latter into position to lock the universal bar and thus take the direct thrust strain off the locking arm 25^a.

The forward end of the locking bar, which is designated as 25, constitutes the carriage locking element and is provided with an outward bend 30 therein which brings it to a point outside of the side plate 3 of the frame. The arm is then bent rearwardly and upwardly, forming an inclined portion 31 which at its upper end is turned straight up and brought under the overhanging flange 5 of the top adjacent to the side and is there bent outwardly to form a loop 32 which brings the locking bar just under the lower lip of the flange 5, where-

upon the bar is bent up at 33 and again bent over at 34 to overlie the top 4 and to extend crosswise of the machine to a point opposite the draw strap stud 16 when the carriage is in the middle position. The 70 arm is then bent up at 35 and bent forward horizontally at 36 and provided at its end with a yoke 37, the arms of which lie horizontally and are adapted to receive between them the stud 16 and thereby to lock the 75 carriage against lateral movement.

It will be noted that when the key actuated locking bar is thrown into operating or locked position with its yoke member 37 pressed against the carriage pin 16 and the 80 yoke 26 and arm 27 pressed against the line lock bail and universal bar, it will prevent the lock frame from being shifted to the left sufficiently for its flange 20 to clear the frame, inasmuch as the frame itself will 85 prevent the lock being shifted to the right, even after the retaining rivets are withdrawn, the locking bar, which may be broadly considered as the key actuated locking bolt, will serve in its locked position to 90 hold the lock casing fast in position in the frame.

In operation, to unlock the typewriter, the turning of the lock will shift the yokes 26 and 37 simultaneously rearwardly, thus 95 releasing the draw strap stud 16 of the carriage and also both the universal bar and the line lock bail, leaving the latter free to assume its upright position. The typewriter is then free for use. To lock it, the 10 key controlled movement will advance the yokes forwardly, the yoke 37 embracing the stud 16 and the yoke 26 not only engaging and locking the universal bar but also forcing the line lock bail into locked position behind the bar.

The particular manner of constructing the locking arm for the carriage has in view to provide the maximum brace from the frame itself, but it will be obvious that this 11 may be widely varied so long as the carriage lock is operable from the typewriter lock and adapted to move it into engagement with a suitable part of the carriage. In like manner the particular construction 11 of the universal bar lock may be varied and it may be used separately or in combination with the carriage lock and it may also be adapted to lock the universal bar without reference to the line lock bail or, 12 by shortening the yoke arm 27, to lock the universal bar solely through the instrumentality of the line lock bail.

With these modifications in mind, what I desire to secure by Letters Patent, is:—

1. The combination with a typewriter having movable parts, of a key-controlled lock adapted to be attached to the typewriter and having a bolt formed of an elongated rod shaped to engage and lock one of said 13

movable parts and when so engaged to prevent the detachment of the lock from the typewriter.

2. The combination with a typewriter having type bar levers and a universal bar, of a key controlled lock rigidly attached to the typewriter, and a bent bar actuated as a bolt by the lock and disposed in position to engage and lock the universal bar and through it the type bar levers.

3. The combination with a typewriter having a universal bar, a line lock bail and type bar levers, of a key controlled lock rigidly attached to the typewriter, having means actuated by the key to engage and lock the universal bar and to move and hold the line lock bail in position to coöperate with said means in locking the universal bar.

4. The combination with a typewriter having a universal bar and a line lock bail, of a key controlled lock rigidly attached to the typewriter, having means actuated by the key comprising a yoke member adapted to straddle the line lock bail and, in one operating position, to force the bail into position to lock the universal bar and, in its other position, to leave the bail and universal bar free for normal manipulation.

5. In a typewriter the combination of a universal bar and a line lock bail having a slot therein, with a key-controlled lock permanently attached to the typewriter, having a bolt bar provided with a yoke at one end and a vertical pin loosely mounted thereon which is passed through the slot in the bail, the yoke being adapted to straddle and force the bail into position to lock the universal bar.

6. The combination with a typewriter frame and a carriage thereon, of a key-controlled lock permanently attached to the frame having a bolt bar operable by the key and movable thereby toward and from the carriage, and a yoke on said bar adapted to straddle a permanent part of the carriage and lock the latter.

7. The combination with a typewriter frame and a carriage thereon, of a key controlled lock rigidly attached to the frame, having a locking arm operable by the key and movable thereby toward and from the carriage and having an intermediate bend which engages under the top portion of the typewriter frame, and a yoke on said arm adapted to straddle a portion of the carriage and lock the latter, substantially as described.

8. The combination of a typewriter frame having a top plate with down turned side edges, a carriage movable transversely across the top of the frame having a stud thereon, a

key controlled lock attached to the frame, said lock having a rod operable by the key and bent to provide an intermediate loop portion which engages under the overhanging side edge of the top of the frame, and a yoke on the end of said arm which is adapted to straddle said stud on the carriage to lock the latter, substantially as described.

9. The combination with a typewriter having a carriage, a universal bar and type bar levers, of a key controlled lock permanently attached to the typewriter, said lock having means operable by the key to simultaneously lock the carriage and the universal bar against movement, substantially as described.

10. A typewriter locking mechanism comprising a key lock having a bolt member adapted to straddle and move into locking position with a line lock bail.

11. A typewriter locking mechanism comprising a key lock having a bolt member provided with a yoke which is adapted to embrace a portion of the typewriter carriage and lock it against movement.

12. A typewriter key locking mechanism adapted to be attached to a typewriter and having a bolt member adapted to simultaneously engage the carriage controlled line lock bail and the carriage and lock them against movement in either direction.

13. The combination with a typewriter having a carriage and a means for locking the type bar levers, of a key controlled lock mounted on the typewriter, having members disposed to engage and lock both the typewriter carriage and said type bar locking means, said members when in locked position being adapted to hold the key controlled lock against removal.

14. A key controlled lock mechanism for typewriters adapted for attachment to a typewriter having a lock bolt comprising a rod having yokelike members at each end adapted to engage and interlock with a plurality of the movable typewriter elements which it is desired to lock against movement.

15. The combination with a typewriter having a carriage and type bar lever locking means of a key lock having a casing shouldered to seat in a corner of the typewriter frame and overlap behind the bottom and side edge thereof, and a bolt disposed to engage said carriage and said locking means and positively hold said casing in engagement with said frame.

In testimony whereof I affix my signature.
MILTON M. BLUM.
